[57] CLAIM

The ornamental design for a package for ball, pump, and cones, as shown and described.

DESCRIPTION

FIG. 1 is a top, front, and right side perspective view of a package for ball, pump, and cones showing our new design, the broken-line disclosure of the ball, pump, and cones being for illustrative purposes only and forming no part of the claimed design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.

FIG. 1

FIG. 4

FIG. 5
